CAR SIDE FRAME

Charles S. Johnston, Glencoe, Ill.

Application January 19, 1931. Serial No. 509,797

18 Claims. (Cl. 105—406)

My invention relates to railway rolling stock and consists in novel side frame structure for freight cars.

The object of my invention is to provide a side frame integral structure including vertical posts, diagonal braces, and a top chord, adapted to be assembled, as a unit, with the car underframe side sill to form a truss structure. Such construction eliminates many of the joints present in the usual built up structures thereby overcoming the rapid deterioration cause by dust and grit working into the joints between the many parts secured together and this results in greater permanence and also adds to the strength of the structure by replacing bolts and rivets with continuous metal. The integral structure also eliminates play between the parts such as arises from the loosening of connecting elements in the usual built up structure and also eliminates in the preferred form of my invention, embodying cast structure, a great deal of metal otherwise required, for all of the metal used may be disposed most advantageously for a given weight as no particular section need be maintained except where required for strength.

These objects and others are obtained in the structure illustrated in the accompanying drawing in which—

Figure 1 is a top view of a half of my side frame arranged for a railway gondola car.

Figure 2 is an elevational view of the same half of the side frame showing also the car wall.

Figures 3 and 4 are vertical transverse sections taken substantially on the corresponding section lines of Figure 2, Figure 3 also including the adjacent portion of the underframe.

Figure 5 is a horizontal section taken on the line 5—5 of Figure 2 and showing the adjacent portion of the underframe.

The selected embodiment of my invention comprises a side frame formed in three parts including an end section 1, a center section 2 (of which only one longitudinal half is shown) and an opposite end section, not shown, corresponding to section 1. Formed integrally in each end section are a top chord 3, end post 4, intermediate post 5, an inner post 24, diagonal braces 6, and a bottom tie element 7. Formed integrally with the center section are vertical posts 8, a top chord 9, a bottom tie member 10, and diagonal braces 11, 11a, and 11b. The top chords 3 and 9 and the vertical posts 5, 24, and 8, 8 are of Z cross section, the diagonal braces 6, 6, 11, 11a, and 11b are of channel section, and the bottom tie mem-

bers 7 and 10 are of angle section as shown in Figure 3. The end post is provided with a vertical flange 12 for hooking over the car end boards. The side sill 22 of the underframe mounting my side frame forms the bottom chord of the side frame girder and elements 7 and 10 are of comparatively light construction and provided to facilitate handling the frame portion when detached from the underframe. A suitable underframe is illustrated in co-pending application, Serial No. 511,062, filed Jan. 24, 1931, in the names of C. F. Frede and E. G. Hallquist.

Each end section is secured to the adjacent section by means of rivets or other fastening elements through the overlapping top chord elements. Chord 9 is depressed at its end to receive the inner end of chord 3. Diagonal brace 11 merges with the end of center section top chord 9 in a substantially square gusset 16 with flanges on two sides forming a pocket to overlap a similar gusset on section 1, and elements 16 and 17 are riveted together for further strengthening the joint. Each inside angle of the structure is merged in a reinforcing gusset.

The vertical posts extend below the level of the car floor and are secured to the underframe sill 22 and transoms 15. Figure 5 shows a joint between an I shaped transom of the underframe and a vertical post 8. The underframe structure shown is preferably of integral construction and includes plates 21 and ribs 20 for stiffening the joint.

Obviously, other details of construction such as the shape of the various members, the number of panels in each girder section, the number of sections embraced in the complete frame, the type of car in which my invention is used, and the manner of joining the parts as to whether rivets, bolts, or welding is used, may be varied without departing from the spirit of my invention. My idea further embraces a complete side frame formed of a single casting. I contemplate the exclusive use of all such variations as come within the scope of my claims.

I claim:

1. In a railway car side frame, two adjacent sections having top and bottom structural elements, said sections being joined together at the top only, at least one of said sections having a sloping end forming an open angle with the adjacent end of the other section, and said bottom elements being interrupted between the adjacent lower extremities of said sections.

2. A railway car side frame comprising end sections and an intermediate section, said in-

- termediate section having a top chord, diagonal braces, vertical posts, and a bottom tie member cast integral, the diagonal braces being of channel section and the vertical posts being of Z section. 80
3. A railway car side frame unit comprising a plurality of sections secured together, the end section thereof having vertical posts, diagonal braces, top chord, and bottom tie member all cast integral, said top chord extending beyond the inner vertical post, and an integral gusset in the angle formed by said post and the projecting portion of said chord. 85
4. A railway car side frame unit comprising a plurality of sections, gussets formed in the upper adjacent corners of said sections positioned to overlap each other when said sections are placed together, and means for securing said gussets together. 90
5. A railway car side frame open truss unit comprising a plurality of sections each having vertical post members, diagonal brace members, a top chord member, and a bottom tie member all cast integral, the unit also including a gusset integral with and merging with certain of said members to provide for attachment to a like adjacent unit. 95
6. In a railway car side frame unit, a plurality of sections, each including vertical posts, diagonal braces, a top chord, and a bottom tie member formed in a single casting, said vertical posts extending below the bottom tie members for engaging the car underframe. 100
7. In a railway car side frame rigid truss unit, an end section having a top chord and end posts cast integral, one of said end posts forming an angle for engaging the car end wall and the other being arranged for attachment to adjoining side wall structure. 105
8. A railway car side frame unit integral structure comprising end posts, a center post, a top chord, diagonal braces extending from the lower portions of said end posts to the upper portion of said center post, the lower portions of said posts and diagonals being arranged for connection to an underframe side sill. 110
9. A railway car side frame unit integral structure comprising end posts, a center post, a top chord, diagonals extending from the lower portion of said center post to the upper portions of said end posts, said top chord extending a substantial distance beyond said end posts, diagonals extending from the lower portions of said end posts to the ends of said chord, and a tie member connecting said posts and terminating at said end posts. 115
10. In a railway car side frame unit integral structure, an inner post, an outer post, a top chord connecting said posts and projecting a substantial distance beyond said outer post, a diagonal extending from the lower end of said inner post to the upper end of said outer post, a diagonal extending from the lower end of said outer post to the end of said chord, and a tie connecting the lower portions of said posts and diagonals and terminating with said outer post. 120
11. A structure as set forth in claim 9 in which the lower ends of said posts and diagonals extend below said tie for attachment to the car underframe side sill. 125
12. A structure as set forth in claim 10 in which the lower ends of the posts and diagonals extend below said tie for attachment to the car underframe side sill. 130
13. In a railway car side frame truss structure, the combination with an underframe longitudinal, of a plurality of integral truss castings, and means securing said castings together at the top only and to said underframe, whereby said longitudinal constitutes the bottom chord element of each truss. 135
14. In a railway car side frame, the combination of a rigid truss unit including end posts, a top chord, diagonals, and a substantially lighter bottom tie, said chord, diagonals, and tie constituting the sole connection between said posts, with an underframe side sill secured to the lower portions of said posts and diagonals and constituting the bottom structural chord of said truss. 140
15. In a railway car side frame, the combination of a series of rigid truss units, each having substantial end post, top chord and diagonal elements and a comparatively light bottom tie, said elements and said tie constituting the sole connection between said end post elements, with a substantial underframe side sill, secured to the lower portions of said posts and diagonals and constituting the bottom chord of all of said units. 145
16. In a railway car side frame truss, a continuous rigid top chord, vertical posts and diagonals, and relatively light tie elements connecting certain of said posts, said elements being omitted between others of said posts, and a continuous rigid underframe side sill secured to the lower portions of said posts and diagonals and constituting the bottom chord of said truss. 150
17. In a railway car side frame truss, substantial top chord and end post elements and relatively light bottom ties, said posts depending beneath said ties, and an underframe side sill secured to the lower portions of said posts and constituting the bottom chord of the truss. 155
18. In a railway car side frame, a rigid truss section including a top chord and end posts, one of said posts being angular in section for attachment of car end wall structure and the other post having an element adjacent its intersection with said top chord forming a connection for adjoining side wall structure. 160
